ATTORNEYS

UNITED STATES PATENT OFFICE.

JOHN H. MORRISON, OF KINGSBRIDGE, NEW YORK.

SKATE-CLAMP.

SPECIFICATION forming part of Letters Patent No. 702,145, dated June 10, 1902.

Application filed February 4, 1902. Serial No. 92,582. (No model.)

To all whom it may concern:

Be it known that I, JOHN H. MORRISON, a citizen of the United States, residing at Kingsbridge, in the county of New York and State 5 of New York, have invented certain new and useful Improvements in Skate-Clamps, of which the following is a full and complete specification, such as will enable those skilled in the art to which it appertains to make and 10 use the same.

The object of this invention is to provide an improved clamp for holding skates in the operation of grinding or sharpening the same; and with this and other objects in view the 15 invention consists in a device of the class specified constructed as hereinafter described and claimed.

The invention is fully disclosed in the following specification, of which the accompanying drawings form a part, in which the separate parts of my improvement are designated by the same reference characters in each of the views, and in which—

Figure 1 is an end view of my improved 25 skate-holder and showing the method of using the same, and Fig. 2 a plan view of the construction shown in Fig. 1.

In the practice of my invention I provide a clamp for the purpose specified, which 30 comprises a bottom portion or base *a*, with which are connected two vertical screws *b*, each of which is provided with two clamp-nuts *c*, which are in the form of ordinary thumb-nuts. The screws *b* are connected with the base portion *a* at or near the opposite ends thereof in any desired manner, and mounted on these 35 screws between the clamp-nuts *c* are two clamping-bars *e*, the central parts of which are preferably curved backwardly, and in practice the runner *f* of the skate *g* is passed 40 between the clamping-bars *e* and securely clamped in position by means of the nuts *c*. I have also shown in the drawings a table *h*, provided with supports *i*, in which is mounted a shaft *j*, having an emery or other wheel *k*, and the object of providing two nuts on each of the screws *b* and mounting the clamping-bars *e* between the same is to provide 45 means for vertically adjusting the clamp or the bars thereof, between which the runner of the skate is passed, so that the said runner will be in direct line with the center of

the stone *k* when the runner is held in proper position, as shown in Fig. 1, and by this means I provide for grinding the bottom surface of 55 the runner smoothly and evenly and avoid the grinding thereof at the opposite edges.

The table *h* and stone *k* are only shown for the purpose of indicating the operation of the device and the object of making the clamp 60 in the manner described, and any suitable support may be substituted for said table. It will be understood, of course, that the clamp is moved back and forth across the table, so as to grind the entire bottom portion 65 of the runner of a skate, and my invention is not limited to the table or support, as it is possible to operate the device without any other support than the support of the stone.

Having thus fully described my invention, 70 what I claim as new, and desire to secure by Letters Patent, is—

1. A device of the class described comprising a base, vertical screws near the opposite ends thereof, each of which is provided with 75 two set-nuts and two clamping-bars mounted on said screws between said nuts, substantially as shown and described.

2. A device of the class described comprising a base, vertical screws near the opposite 80 ends thereof, each of which is provided with two set-nuts and two clamping-bars mounted on said screws between said nuts, the central portions of said bars being curved backwardly, substantially as shown and described. 85

3. A clamp of the class described comprising a base-plate, vertical screw-threaded end members connected therewith, two vertically-movable clamping-bars mounted on said end members, and two nuts mounted on each of 90 said end members above and below said bars, whereby the vertical position of said bars may be adjusted on said end members, and whereby said bars may be clamped together, substantially as shown and described. 95

In testimony that I claim the foregoing as my invention I have signed my name, in presence of the subscribing witnesses, this 3d day of February, 1902.

JOHN H. MORRISON.

Witnesses:

T. A. STEWART,
C. E. MULREANY.
